BRACELET

Russell A. Funk, Torrance, Calif.
(315 E. Washington Ave., Santa Ana, Calif. 92701)

Filed Nov. 8, 1965, Ser. No. 88,046

Term of patent 14 years

(Cl. D45—4)

FIG. 1.

FIG. 2.

FIG. 3.

FIG. 4

FIG. 1 is a front elevational view of a bracelet showing my new design;

FIG. 2 is a bottom edge view thereof;

FIG. 3 is an enlarged sectional view taken on line 3—3 of FIG. 1; and

FIG. 4 is a rear elevational view thereof on a reduced scale.

The dominant features of the design reside in the full line portions of the drawing.

I claim:

The ornamental design for a bracelet, as shown and described.
